TO COOPER HEWITT ELECTRIC COMPANY, OF HOBOKEN, NEW JERSEY, A CORPORATION OF NEW JERSEY.

SINGLE-PHASE GAS OR VAPOR ELECTRIC APPARATUS.

1,163,707.

Specification of Letters Patent. Patented Dec. 14, 1915.

Original application filed June 13, 1903, Serial No. 161,282. Divided and this application filed May 26, 1911. Serial No. 629,632.

To all whom it may concern:

Be it known that I, PERCY H. THOMAS, a citizen of the United States, and resident of Montclair, county of Essex, State of New Jersey, have invented certain new and useful Improvements in Single-Phase Gas or Vapor Electric Apparatus, of which the following is a specification.

In an apparatus of the character shown in certain patents to Peter Cooper Hewitt, for example Patents 682,690 to 682,699 inclusive, dated September 17th, 1901, which is operated on direct current circuits, it has been customary in starting to apply to the terminals of the apparatus a momentary current of higher potential than that upon which the apparatus is designed to be operated. In employing alternating currents, it is possible to apply to the starting band a higher potential derived from the supply circuit.

When the described reluctance to starting has once been broken down, current may continue to flow through the apparatus provided the applied electro-motive-force is sufficiently high and also provided that the direction of flow be maintained uniformly. When, however, currents of varying value or of alternate direction are applied to the apparatus, the electrode reluctance is liable to be re-formed should the current value drop below a certain minimum, and is certain to be re-formed when the direction of flow is reversed. Thus in operating apparatus of this class by means of alternating currents or currents which vary considerably in value, provision has to be made for reinforcing the lower values when the current is of uniform direction and for repeatedly starting the apparatus whenever the direction of the current changes.

It has been proposed to provide means for the purpose indicated by placing a choke coil in series with the apparatus which will store energy while the current is increasing and discharge the stored energy or a portion of it in the original direction of flow when the current falls. With a choke coil of sufficient capacity, the energy stored on the rising current will be sufficient to maintain current through the negative electrode until the supply circuit shall again tend to increase the current flow in the proper di-

rection. In connection with this general arrangement of circuits and apparatus, various organizations have been proposed for preventing the negative alternations from undoing the work of the positives. For example, the amount of energy required from the choke coil is considerably lessened if a path be provided for the negative alternations through the apparatus by means of a second positive electrode. With such an organization, both the positive and negative alternations tend to pass through the lamp in the same direction. Meanwhile, the function of the choke coil in delivering energy enough to supply current for the short period between alternations is constantly called into play.

It might be supposed that in operating the vapor apparatus upon a single phase alternating current, the capacity of the choke coil might have to be considerable, but I have found that in order to maintain the operation of the apparatus after it has once been started, the choke coil need not be of excessive size. It is desirable, however, that an extra potential should be applied to enable the choke coil in the first alternation after starting to absorb a sufficient amount of energy so that it may discharge the energy necessary to maintain the lamp over the first zero point, without falling below the minimum current.

It is the object of the present invention to provide means for supplying this extra initial potential, as will presently appear, it being understood that the additional voltage thus withdrawn from the source will generally be removed after the starting of the apparatus. This makes it possible to obtain economical conditions during operation, and provides that the extra potential called into use at the starting of the apparatus shall constitute only a temporary demand upon the system.

I avoid the use of a supplemental electrode by applying to one or both of the positive electrodes a supplementary electro-motive-force and transferring the positive electrode or electrodes to the normal running point on the transformer winding after starting, without the interruption of the circuit.

The high potential at the starting point

may be obtained, if desired, through a snap or quick break switch just as in a direct current lamp. In this case it is sometimes necessary to close and open the switch a number of times in order to insure that the mechanical break should occur at a favorable portion of the cycle for producing a high potential impulse.

I have illustrated my invention in the accompanying drawing, which shows the application of my invention to a mercury vapor device having two anodes, a cathode and utilizing an inductance for controlling the operation of the device.

15 1 is the container of a lamp of the character described above, the same containing, in this instance, a negative electrode, 5, of mercury and positive electrodes, 2 and 3, which may be of iron.

20 The device is fed from an auto transformer winding, 21, supplied from two mains 13, 13. The cathode, 5, of the device is connected through an inductance, 7, to an intermediate point, 8, of the winding 21. 25 Other portions of the windings 14, 14, respectively on the right and left hand ends of the winding 21, have resistances 18, 18, connected in parallel with them, there being provided arms, 19, 19, adapted to contact either with the windings 14 directly at two 30 points or adapted to contact with intermediate points on the resistances 18, 18.

The conductors 13, 13 are assumed to be connected with a source of single-phase alternating current. The operation of the lamp is then as follows: Assuming, for example, that the electrode 2 has a positive potential with regard to the negative electrode at the time of the application of the 40 critical strain, current flows from 2 to 5, reaching finally the proper value for the electro-motive-force supplied and at the same time storing energy in the choke coil 7. During the latter part of the first alternation, as the voltage upon the positive electrode 2 falls to zero, the energy previously stored in the choke coil 7 continues the flow of current in the original direction through the coil until the potential upon the electrode 3 becomes positive in its turn, whereupon electrode 3 will itself support the current through the lamp and, as its value rises in the second alternation, will increase the current through the choke coil 7 to the 50 maximum at the time at which it is returning toward zero. As before when the voltage of the electrode 3 becomes too small to support the current through the choke coil, 7, this coil supplies energy keeping the current flowing, though at a decreasing intensity, until electrode 2 after having had a negative value during the second alternation again becomes positive in the third alternation, when it is utilized to again support the current through the lamp and the 55

choke coil 7, and so on, as long as the lamp operates.

The function of the supplementary windings 14 and the positive electrodes is to supply an additional electro-motive-force during the alternation within which the critical or starting strain is applied. It is evident that during this first alternation, the current must reach its maximum value after starting from zero, whereas, when once the 70 lamp is operating normally, this maximum current must be reached in one alternation, starting, not from zero, but from the minimum value reached during the operation which must at least be the minimum operating current of the lamp. Once the lamp has reached a normal running condition, the supplementary voltage supplied by the windings 14, 14 is no longer required and in fact will cause a waste of energy and disturbance of the operation of the lamp and should be removed from further operation. 80

The conductors 9 and 10 are joined to the windings of the auto-transformer 21 through resistances 18, 18, provided with 90 movable arms 19, 19. The starting band is connected by a wire 26 with the conductor 9, while a shunt circuit 27 containing a quick break switch 16 and a resistance 17 is connected between the conductors 9 and 8. 95

The switch arm 19 at the left is represented at starting position, while the corresponding arm at the right is represented as having been moved from the starting position to the opposite extreme position. An 100 extra winding 14 is added at both ends of the winding 21, and each is connected through one or the other of the adjustable resistances to a separate positive electrode in the lamp. With the switches in the 105 starting position, the supply circuit 13, 13 is closed and the snap or quick-break switch 16 is operated. By the action of the switch 16 and the resistance 17 and the coil 7 a high potential impulse is created at the 110 starting band and this is reinforced by the energy developed in the windings 14, 14.

The lamp having been once started into operation in this way, the switches 19 are moved from the starting position to the operating position (the latter being illustrated, as already explained, by the switch at the right hand side of the figure) and the operation continues with the windings 14, 14 disused. 120

It is known that the critical strain may be applied to the apparatus through other instrumentalities than the starting band, and if desired any means equivalent to the starting band may be substituted therefor. 125

This application is a division of my application Serial Number 161,282, filed June 13th, 1903, and a companion to my application Serial Number 169,091, filed August 11th, 1903, patented March 1st, 1910, No. 130

951,085; and a companion of my application Serial Number 540,738 filed January 29th, 1910.

I claim as my invention:

- 5 1. In a system of electrical distribution, the combination with a supply, a mercury vapor apparatus comprising a highly exhausted container and suitable electrodes therefor, including a plurality of anodes, of
- 10 means for supplying current alternately through two anodes, means for separately changing the supply voltages applied to the two anodes, and energy storing means for steadily the total flow of current.
- 15 2. In a system of electrical distribution, the combination with a supply, a mercury vapor apparatus comprising a highly exhausted container and suitable electrodes therefor, including a plurality of anodes, of
- 20 means for supplying symmetrical relatively high voltage upon two anodes and means for applying symmetrical relatively lower

supply voltages upon the two anodes and discontinuing the supply from said higher voltage.

25

3. In a system of electrical distribution, the combination with a rectifier comprising an exhausted container, anodes and a cathode therein, of an exciting winding supplied from a single phase source of alternating current and connected to said cathode at an intermediate point, and means for independently connecting each of the anodes at will directly to any one of a number of points of different potential in said exciting winding.

30

Signed at New York in the county of New York and State of New York this 25th day of May A. D. 1911.
